UNITED STATES PATENT OFFICE

120,182

DESIGN FOR A BOLERO JACKET

Margit Fellegi, Los Angeles, Calif.

Application November 14, 1939, Serial No. 88,274

Term of patent 3½ years

To all whom it may concern:

Be it known, that I, Margit Fellegi, a citizen of United States and residing at Los Angeles, in the county of Los Angeles and State of California, have invented a new, original, and ornamental Design for a Bolero Jacket, of which the following is a specification, reference being had to the accompanying drawing, forming part thereof.

In the drawing, Figure 1 is a front perspective view and Figure 2 is front perspective view in opened position of the article, showing my design.

I claim:

The ornamental design for a bolero jacket, as shown and described.

MARGIT FELLEGI.
